UNITED STATES PATENT OFFICE.

LE GRAND M. ANWAY, OF NEW YORK, N. Y.

AUTOMATIC MECHANICAL BOILER-CLEANER.

SPECIFICATION forming part of Letters Patent No. 373,712, dated November 22, 1887.

Application filed August 10, 1887. Serial No. 246,565. (No model.)

To all whom it may concern:

Be it known that I, LE GRAND M. ANWAY, of New York, in the county of New York and State of New York, have invented a new and 5 useful Improvement in Automatic Mechanical Boiler-Cleaners; and I do hereby declare that the following is a full, clear, and exact description of the same.

My invention is an improved automatic mechanical boiler-cleaner of that class in which the impurities are removed from the surface by the action of the current of water within the boiler acting against a collector, which receives the impurities and discharges them 15 through a suitable pipe into a drum in which the sediment is collected.

My invention consists of an improved form of the collecting-diaphragm and in certain details of construction, all as hereinafter explained.

In the drawings, Figure 1 represents a boiler, partly in central longitudinal section and partly in side elevation, showing the collecting-diaphragm in place in like section. Figs. 25 2 and 3 represent the collecting-diaphragm detached, and Fig. 4 shows a modified arrangement of the settling-drum.

In the drawings, A indicates the boiler, here used to represent any kind or form of 30 boiler in which the invention may be used. Above the flues a in the upper part of the boiler is a partial head or collecting-diaphragm, B. It extends across the boiler from side to side, and vertically above and below 35 the limit, 1 2, of high and low water in the boiler. In form the collecting-diaphragm is curved in two directions—that is to say, on horizontal and vertical planes, as represented in Figs. 2 and 3. On the lower edge, which is 40 practically horizontal and straight, is a plate, b, having on its edge an upturned flange, c; or this may be turned slightly in to overhang the plate. This flange and the plate extend also from side to side. In the center of the diaphragm is an opening made in elongated vertical form, preferably oval in length, to correspond with the upper and lower levels of the water. This opening is the mouth of a 45 pipe, D, which extends to the rear and is connected with the pipe d, leading to the settling-drum. As the opening in the diaphragm and mouth of the pipe D are, as explained, oval

or vertically elongated, the pipe D must be conical or tapering to the rear. I have found that if it be made with a true taper—that is 55 to say, with an upper and under surface both inclined, or with the upper surface inclined from front to rear downward—the scum will strike against this upper surface when passing through the pipe D, and will thus be obstructed, while the clear water underneath 60 will pass on through the pipe. I have therefore devised the pipe in the form shown. The upper surface of the pipe is horizontal and the under edge inclined, so that there is no 65 obstruction to the passage of the scum, and the water underneath passes freely up the inclined under surface of the tapering pipe.

The diaphragm is formed for convenience of construction in two parts, and these are united 70 on a central vertical line. In this way the parts can be introduced separately through the man-hole and united and fixed in place within the boiler by links e, or in any convenient way. From the end of the tapering pipe 75 D the pipe d extends horizontally to the vertical pipe f, which communicates with the lower part of the settling-drum. The settling-drum is vertical in Fig. 1, and has a blow-off or cleaning cock, g, and an upper cock, h, from 80 which the oil, magnesia, or other light substances may be drawn off. From the upper part of the settling-drum E is the return-pipe k, which is shown as carried under the boiler and outside thereof; but it may be passed 85 through the boiler. The position may be varied, however, according to the nature or form of the boiler. The front end is provided with a cock, l, and is turned up and enters the boiler in position to discharge on the fire-plates at the 90 front and over the grate F.

The collecting-diaphragm may be provided with one or with several openings and tapering pipes, as shown in dotted lines in Figs. 2 and 3. In Fig. 2 one is thus shown on each 95 side, and curved tapering pipes on the same principle as the central pipe, D, are united to the pipe d by suitable unions to give greater collecting capacity.

In Fig. 4 is shown a horizontal settling-tank 100 with inlet and outlet pipes as represented. This may be used instead of the vertical form shown in Fig. 1.

In operation the surface-current of the boiler

is from left to right in Fig. 1. The collector is near the right-hand end or rear of the boiler, and faces to the left or front. Its vertical extent and the vertical extent of the opening or 5 openings adapt it to work with high or low level of water. The current impinges against the curved face of the collecting-diaphragm, and the scum carried on the surface is turned toward the center. The flange is below the 10 lower water-line, so that the current always passes over it and strikes the face of the collector; but the flange arrests any reflex flow from the face of the collecting-diaphragm, and thus prevents any under-currents from forcing 15 and carrying the scum under the collector. The scum caught is thus drawn and forced into the tapering pipe or pipes D, and passes to the settling-drum described. The flange may be formed with a notched or serrated upper edge 20 to allow the direct current to pass more readily over it.

A valve, *m*, is placed at the junction of the pipe *d* with its vertical pipe. In order to clean the settling-drum, this is closed, and also that 25 at the front end of the pipe. Then by opening the stop-cock at the lower end of the collecting-drum the steam contained in the drum is allowed to blow off, and then the current may be passed through to the drum in either 30 direction by opening either the cock *m* or *l*. The return-pipe is joined to the drum a little below the upper end, so as not to interfere with the oil and other substances on the surface of the water in the drum. The arrangement 35 is the same in the horizontal drum, the cock *o* being the draw-off cock for oil, &c., and for the return-pipe. The circulation between the boiler and mud-drum *E* is kept up by the difference in temperature in the contents of the two chambers, the water as it is 40 heated constantly rising to the surface within the boiler and passing off through the pipe *d*, aided by the pressure of the steam, and its place being taken by water from the chamber *E* entering at the bottom of the boiler. 45

By discharging the return-water from the drum on the fire-plates they are prevented from undue heat, and are thus saved from more rapid destruction.

50 My invention is especially well adapted to locomotive-engines, as the action of the collecting-diaphragm is not affected by the movement of the water from side to side in passing around curves; but it is not at all limited to 55 these engines, but is valuable for any. The

return-pipe is smaller in diameter than the inlet-pipe, and by reason of this the circulation is checked at the return-pipe in the settling-drum, thus allowing the sediment to settle. 60

I claim—

1. In a boiler, and in combination therewith, the collecting-diaphragm *B*, arranged vertically and having the horizontal plate *b* upon its lower edge, the said horizontal portion being formed with an upturned flange, *c*, along its front edge, the diaphragm *B* having an opening, a settling-drum, and the pipe leading from the collector to the drum. 65

2. In a boiler, and in combination, a collecting-diaphragm curved on horizontal and vertical planes, with a plate and upturned flange, an opening in the collector, and a pipe leading to a collecting-drum, substantially as described. 70

3. In a boiler, and in combination, a collecting-diaphragm having a plate and upturned flange, and formed with vertically-elongated openings, a tapering pipe joined to said openings, horizontal on its upper surface and inclined to the rear on its lower surface, a collecting-drum, and a pipe from the said tapering pipe to the drum, substantially as described. 75

4. In a boiler, and in combination, a collecting-diaphragm curved on horizontal and vertical planes, a plate with upturned flange on its lower edge, a tapering pipe having a vertically-elongated mouth, a settling-drum, and connecting and return pipes, substantially as described. 85

5. In a boiler, and in combination, the diaphragm *B*, curved in horizontal and vertical planes, and having a horizontal plate, *b*, said plate being provided with an upturned serrated flange along its front edge, a settling-drum, and suitable connections from the collector to the drum, substantially as described. 90

6. In combination, the boiler, the grate *F* under the same, the collecting-diaphragm in the boiler, the settling-drum, a pipe leading from the collector to the settling-drum, and the return-pipe *k*, entering the boiler at a point directly over the fire-plates and the grate, substantially as described. 95 100

In testimony whereof I have signed my name to this specification in the presence of two subscribing witnesses.
